UNITED STATES PATENT OFFICE.

EMIL OFFERKUCK, OF SPRINGFIELD, OHIO, ASSIGNOR TO THE SUPERIOR GAS ENGINE COMPANY, OF SPRINGFIELD, OHIO, A CORPORATION OF OHIO

INTERNAL-COMBUSTION ENGINE.

Application filed April 17, 1922. Serial No. 554,031.

To all whom it may concern:

Be it known that I, EMIL OFFERKUCK, a citizen of the United States, residing at Springfield, in the county of Clark and State of Ohio, have invented certain new and useful Improvements in Internal-Combustion Engines, of which the following is a specification.

This invention relates to improvements in internal combustion engines, it relating particularly to that type of engine in which the explosive charge is formed in the cylinder and ignited by an ignition member which is maintained in heated condition by the burning fuel.

An object of the invention is to provide improved means for scavenging the cylinder of a two-cycle engine; a more particular object in this connection being the provision of an air supply under pressure which is automatically admitted to the combustion chamber by the reduction of pressure in the cylinder when the exhaust port is uncovered.

A further object of the invention is to provide improved means for preventing the overheating of the ignition member; a more specific object in this connection being to provide means for injecting a quantity of air under pressure at a point in close proximity to the ignition member which acts to cool the said member.

A further object of the invention is to provide means for also injecting water into the combustion chamber at a point in close proximity to the ignition member to further assist in cooling said member under certain conditions of operation.

A further object of the invention is the provision, in a two-cycle engine, of an automatic air supply to not only cool the ignition member and scavenge the cylinder, but form a part of the explosive mixture.

In the accompanying drawings:

Fig. 1 is a longitudinal section of the cylinder of an explosive engine to which my improvements have been applied.

Fig. 2 is a side elevation of the same.

Fig. 3 is a sectional view of the air admission valve, the section being on the line 3-3 of Fig. 4.

Fig. 4 is a section on the line 4-4 of Fig. 2.

There is shown in the drawings only so much of the engine as is necessary to illustrate the improvements, the engine shown

being of the two-cycle type. The cylinder is indicated at 1 and is surrounded at its forward end by the usual water jacket 2, a water jacketed head 3 being connected to the forward end of the cylinder and its jacket. An air chamber 4 is formed about the rear end of the cylinder, which is shown as an integral part of the base 5, mounted upon the block 6. The piston is shown at 7, and 8 represents the piston rod which passes through the usual stuffing box 9 in the partition 10 at the rear end of the air chamber 4. The head 3 is formed with a combustion chamber 11 which communicates with the forward end of the cylinder through the restricted orifice 12 and located in this head is a fuel injection valve 13 of any usual type employed in oil burning engines. An igniter member consisting of a cup-shaped part 14 of a well known form is inserted in the open forward end of the cylinder head and has a flange 15 which is secured to the end of the head by the water jacketed cap 16. The interior of the air chamber 4 is brought into communication with the interior of the cylinder when the port 17 is uncovered by the piston at the end of the explosive stroke and an exhaust port 18, also uncovered by the piston at or near the end of the same stroke, places the interior of the cylinder in communication with the water-jacketed exhaust 19.

Mounted on the head 3 is a valve casing 20 which communicates with the air chamber 4 through a pipe connection 21, a valve 21^a being preferably placed in this connection to provide for regulating the air supply. The casing 20 communicates with the interior of the head through the port 22, which port is in close proximity to the igniter cup 14. The chamber 20 has a port communicating with the port 22 and controlled by a valve 23, the stem 24 of which is slidably mounted in the casing 20 and is acted upon by a coil spring 25, interposed between the upper side of the casing 20 and a head 26 on the end of the stem, so as to normally hold the valve to its seat.

Also leading into the interior of the valve casing 20 is a small pipe 27 which has its other end connected at any suitable point with the interior of the water jacket for the cylinder, the point of connection being shown as the place where the water discharge pipe 28 leads therefrom.

Also connected with the interior of the valve chamber 20 is a third pipe 29 which is connected with any suitable source of air supply under pressure such as an air pressure tank (not shown).

The operation is as follows: The igniter cup is first heated by a blow torch to the desired degree of heat to vaporize the fuel and ignite the explosive mixture. Upon each explosive stroke of the piston, air is compressed thereby in the chamber 4, and, through the connection 21, also in the valve chamber 20. As soon as the exhaust port 18 is uncovered at or near the end of the explosive stroke of the piston the air valve 23 will open under pressure and permit a blast of air and water to be sprayed upon the igniter member 14, this air acting also to force out through the exhaust the products of combustion of the exploded charge. At this point air is also admitted through the port 17 which together with the air admitted through the valve 23 mingles with the fuel upon the compression stroke of the piston to form the new charge of explosive mixture; the fuel valve automatically opening at the proper point on the compression stroke of the piston to admit the oil fuel in a well known way.

Having thus described my invention, I claim:

1. In an internal combustion engine, a cylinder and piston; a combustion chamber at the forward end of said cylinder, a restricted passage from said combustion

chamber to said cylinder having end walls projecting outwardly from said passage way, a compression chamber, air inlet and discharge uncovered by said piston, near the end of its power stroke, air passages to said combustion chamber, and an igniter plate inclined below the air inlet, whereby air will be swept down over said inclined igniter plate in a direction at an inclination to said passage way and air likewise will be admitted to said cylinder for scavenging said cylinder.

2. In an internal combustion engine, a cylinder and piston; a combustion chamber at the forward end of said cylinder, a restricted passage from said combustion chamber to said cylinder having end walls projecting outwardly from said passage way, a compression chamber, air inlet, and discharge uncovered by said piston, near the end of its power stroke, air passages to said combustion chamber and an igniter plate projecting towards the passage between said combustion chamber and cylinder and extending across the center line extended of said passage, whereby the air will sweep downwardly over said plate and has a swirling movement past the said center line extended within said combustion chamber while the air is being admitted to the cylinder for scavenging same.

In testimony whereof, I have hereunto set my hand this 14th day of April, 1922.

EMIL OPFERKUCK.
